UNITED STATES PATENT OFFICE

JAMES M. DARBAKER, OF NEW CASTLE, PENNSYLVANIA, ASSIGNOR TO AMERICAN SHEET AND TIN PLATE COMPANY, A CORPORATION OF NEW JERSEY

SHEET FEEDER

Application filed November 5, 1931. Serial No. 573,206.

This invention relates to sheet feeders, one of the objects being to rapidly feed piled sheets, particularly metal sheets, one at a time. Other objects will become apparent.

5 Having reference to the accompanying drawings which show one form of a machine constructed according to the present invention;

Figure 1 is a side elevation.

10 Figure 2 is a top plan.

Figure 3 is an enlarged cross-section, taken from the line III—III in Figure 1.

Figure 4 is a detail from Figure 3.

15 Figures 5 and 6 are enlarged details from Figure 1.

Figure 7 is an enlarged detail from Figure 3.

Figure 8 is a side elevation of Figure 7.

20 Figure 9 is a modification of the structure shown in Figure 4.

Figure 10 is a partial cross-section taken from the line X—X in Figure 1.

Figure 11 is a partial cross-section taken from the line XI—XI in Figure 1.

25 In detail, under one end of a frame 1 is extended a track 2 carrying a truck 3 loaded with a pile of metal sheets 4. This truck is loaded when at a point beyond the frame with the aid of upstanding sheet loading guides 5, one of which is laterally adjustable by a crank handled screw 6 and the other hinged so the truck can travel thereby, when loaded, to a point beneath the frame. A bar 7 locks this hinged member in guiding position.

30 This loaded truck butts into a vertical sheet guide 8 when rolled beneath the frame 1, and a second vertical sheet guide 9 is placed against its rear. The latter guide is horizontally adjustably carried by a gate 10, thus allowing for the entrance and exit of the truck. The drawings show the loading guides 5 much closed to this gate than they 45 actually are in order to keep the scale as large as possible.

When between the guides 8 and 9, the truck is directly over a hydraulic hoist 11 which enables vertical lifting of the piled 50 sheets 4. Horizontally adjustable side

guides 12 prevent lateral movement of the top sheets when and while being lifted.

At the top of the rear sheet guide 9 is a horizontally corrugated substantially flat faced electromagnet 13. When the machine 55 is in operation the hoist 11 raises the piled sheets 4 until the upper ones are somewhat above the bottom of the face of this magnet, as indicated by dotted lines, this magnet then serving to align the sheets and to retard the feeding of doubled sheets.

60 A pair of horizontal bars 14 are positioned along the top of the frame 1 and slidably carry an arrangement which picks the sheets 4 up one-by-one for feeding. A hand wheel operated screw 15, fixed in a journal 16 on the frame 1, is in engagement with this arrangement for regulating its movement.

65 This sheet pick-up arrangement specifically consists of a crank 17, driven by an electric motor 18, which operates a doubly jointed connecting-rod 19, this rod having a short cross-head 20 at its first joint engaging cam surfaces 21 and a longer cross-head or shaft 22 at its end engaging cam surfaces 23. The shaft 22 mounts brackets 22^a which vertically slidably carry a pair of depending rods 23^a having suction cups 24 on their lower ends and a centrally located 70 longer push-rod 25, these members being in each instance urged downward by springs 26. When the crank 17 is rotated by the motor 18 the suction cups 24 will engage the top one of the sheets 4, the push-rod 25, being longer, pushing the center of this sheet 75 downwardly and causing the whole to assume a bent form which will impart a substantial rigidity to it. The cam surfaces 21 and 23 are shaped so that the sheet is first lifted vertically across the face of the magnet 13, whose attractive force will pull off any second sheets accidentally carried by counteracting the suction between the two, and then moved at an upward incline. The 80

85 cam surfaces 21 and 23 are shaped so that the sheet is first lifted vertically across the face of the magnet 13, whose attractive force will pull off any second sheets accidentally carried by counteracting the suction between the two, and then moved at an upward incline. The 90 corrugated face of the magnet serves to jar the sheets lifted thereby and aids in breaking the suction between them. Preferably, a counterbalance 27^a is arranged in connection with the crank 17 to prevent undue 95 100

vibration when these various parts are reciprocated.

The crank 17 is arranged to operate a pair of cam operated poppet valves 27 and 28, 5 these being in connection with the crank 17 and respectively constructed and arranged to create a vacuum in the suction cups 24 just prior to their approach to the top one of sheets 4, and to hold this until the cross-heads 20 and 22 have reached their uppermost movement, when the vacuum is broken and atmospheric pressure admitted.

In order to prevent overheating of the magnet 13 and waste of current, a commutator segment 29 and brushes 30 may be arranged in connection with the operating mechanism of the valves 27 and 28 and in circuit with this magnet, these parts being timed so that the magnet is energized only 20 during the vertical movements of the cross-heads 20 and 22.

A conveyor comprising a plurality of pinch-rollers 31, driven by a motor 32 through chains 33, is positioned on the frame 25 1 so that the first pair of rolls will engage one of the sheets 4 when lifted thereto by the arrangement just described, this latter having been longitudinally adjusted by the screw 15 to hold the sheets near their ends 30 remote from this conveyor so that they may have their ends thrust towards the same. When the sheet is once engaged in the pinch-rolls it is carried forward by them and onto a belt conveyor 34 which carries them to a 35 stand of cold rolls, 35, this conveyor preferably being mounted on a swinging support 36 so that it may be folded back, as indicated by the dotted lines, to permit access to the rolls. Cold rolls are provided generally with a billy roller 37 and it has been found preferable to feed the sheets substantially tangentially thereto by inclining the belt conveyor 34 at the roll end.

Although the magnet 13 is generally 45 effective in removing second sheets it does not under all conditions do so and cannot, of course, prevent the feeding of sheets having bent corners or defective edges. As a safety precaution, therefore, the second pair 50 of rolls is arranged in connection with a micrometric switch 38 operating a sheet deflector 39 by means of a solenoid 40 levered thereto. This deflector is located in the path of the sheets as they leave the third pair of 55 rolls, as shown in the drawings, these being reduced in size at their center and the deflector having a finger 41 which lies in this reduced portion.

When the sheet pick-up arrangement accidentally feeds two sheets the switch 38 will energize the solenoid 40 and throw the deflector 39 into deflecting position. The moment the back ends of these sheets leave the second pair of rolls the solenoid will be de- 65 energized but this will not matter as the

deflector will simply fall on the sheets and then back into its normal position upon complete passage thereof. A chute 42 carries these deflected sheets to a hand truck 43.

In the event of sheets having bent corners or defective edges the switch 38 would not be energized sufficiently long to hold the deflector up to properly deflect the sheet, the rolls operating this switch being therefore constructed to contact only the central portion of the sheets so as to normally be operated only by double sheets. To prevent the feeding of sheets of the character above described the last stand of rolls are made to contact the sheets throughout their length 80 and to operate a pair of trip switches 44 arranged in connection with the motor 32 to stop it. When this happens the defective sheets may be manually removed from the belt conveyer 34 to prevent damage to the cold rolls. These switches, as well as the switch 38, are set differently for differently gaged sheets.

As sheets are removed from those piled on the truck 3 the hydraulic hoist 11 must be 90 operated to maintain the sheets at the proper point on the face of the magnet 13. This is accomplished by controlling the motor 11^a operating the pump of this hoist, by a button switch 45, one of the rods 23 carrying 95 a finger 46 on its upper end for contact therewith. The end of this finger is preferably provided with a vertical adjustment which is fixed so that the switch 45 is closed 100 when the suction cup on the end of this rod falls below the level where the sheets should be. This switch may be arranged to operate the motor for a predetermined interval of time, raising the level of the sheets so that the switch 45 will not be again closed until 105 more sheets have been removed.

The drawings illustrate the switch 45 in circuit with an electromagnetic switch 45^a which controls the current to the motor 11^a which is driving the hydraulic pump for the lift 11. The brushes 30 of the contact commutator segment 29 are also arranged in circuit with an electromagnetic switch 30^a to energize the magnet 13 through a power line thus controlled. Other arrangements 115 than these may prove preferable in actual practice.

A modification in the sheet pick-up arrangement may be made by constructing the faces of the suction cups 24 at downwardly inclined angles towards each other and eliminating the pushrod 25. This will lift the sheets 4 in bent form and impart the desired rigidity thereto.

While a specific form of the invention has 125 been shown and described in accordance with the patent statutes, it is to be understood that it is not desired to limit the invention exactly thereto, except as defined in the appended claims.

I claim:

1. A sheet feeder including spaced vacuum cups having respectively inclined holding faces and means for moving said cups in a vertically straight line direction.
2. A sheet feeder for a pile of sheets including a magnet having a substantially flat horizontally indented face positioned next to and extending above the edges of the upper sheets of said pile, and means for vertically lifting sheets from said pile.
3. A sheet feeder for a pile of sheets including means for lifting a sheet from said pile, an electromagnet arranged with a face proximate the top of said pile and means for energizing said magnet when said first named means is adjacent thereto and for deenergizing the same when this means is remote therefrom.
4. A sheet feeder for a pile of sheets, including the combination of a frame, sheet engaging means carried by said frame, sheet raising means arranged under said frame for movement towards said sheet engaging means, tracks registering with said sheet raising means and leading from said frame, a gate arranged on said frame over said tracks, a vertical sheet guide carried by said gate, and a magnet constructed and arranged for carriage by said gate above said vertical sheet guide to present its attractive face to sheets lifted vertically thereby.
5. The method of vertically removing sheets from a pile of the same consisting in edgewisedly dragging the removed sheets over a corrugated surface to jar them loose from any adhering thereto.
6. A sheet feeder including the combination of a vertically movable holder for piled sheets, electrically operated means for moving said holder, vertically lifting resilient means reciprocably mounted and arranged for the removal of sheets from said holder, a finger resiliently carried by one of said lifting means, and a switch positioned for contact by said finger and arranged in circuit with said electrical means for moving said holder.

In testimony whereof, I have hereunto set my hand.

JAMES M. DARBAKER.
